United States Patent Office

Des. 232,289
Patented Aug. 6, 1974

232,289

SHELF UNIT

Billy Moretine, Chicago, Ill., assignor to International Design Corporation, Chicago, Ill.

Original design application Nov. 10, 1971, Ser. No. 197,643, now abandoned. Divided and this application May 30, 1973, Ser. No. 365,047

Term of patent 14 years

Int. Cl. D6—04
U.S. Cl. D6—18 G

FIG. 1

FIG. 2

FIG. 1 is a perspective view of a shelf unit showing my new design; and

FIG. 2 is a front elevational view thereof.

This is a division of application Ser. No. D.197,643, filed Nov. 10, 1971, now abandoned.

The right side elevation is plain and unornamented. I claim:

The ornamental design for a shelf unit, as shown and described.
